Primary Examiner — Karen S Acker

(74) Attorney, Agent, or Firm — Gutwein Law; Tyler B. Droste

(57) **CLAIM**

The ornamental design for a yard flag stand, as shown and described.

DESCRIPTION

FIG. 1 is an isometric view of a yard flag stand showing my new design;

FIG. 2 is front side view thereof;

FIG. 3 is a rear side view thereof;

FIG. 4 is a left side view thereof;

FIG. 5 is a right side view thereof;

FIG. 6 is a top view thereof;

FIG. 7 is a bottom view thereof; and,

FIG. 8 is an isometric view of the yard flag stand of FIG. 1 shown in a position of use with an unclaimed flag vertical support.

The broken lines depict portions of the yard flag stand that form no part of the claimed design. All other broken lines in FIG. 8 depict environmental subject matter that forms no part of the claimed design.

1 Claim, 7 Drawing Sheets(56)
